J. P. REINECKE

BURNER

Filed April 20, 1923

Patented Nov. 13, 1928.

1,691,169

UNITED STATES PATENT OFFICE.

JOHN P. REINECKE, OF LORAIN, OHIO, ASSIGNOR TO THE HOFFMAN HEATER COMPANY, OF LORAIN, OHIO, A CORPORATION OF OHIO.

BURNER.

Application filed April 20, 1923. Serial No. 633,506.

The present invention relates to gas burners, and the object is to provide devices having ports through which the gas may pass, which burners are practically free from the 5 objectionable feature of "blowing out" when the gas is under what might be termed a high pressure.

A further object of the invention is to provide a burner of such construction that 10 it will not back-fire into the mixer.

A further object of the invention is to provide a burner to be used in situations where it is desired to protect the gas ports from moisture due to condensation.

15 Reference should be had to the accompanying drawings forming a part of this specification, in which Fig. 1 is a top plan view of a burner; Fig. 2 is a central sectional elevation; Fig. 3 is a front elevation 20 of a different form of burner; Fig. 4 is a side elevation with portions in section of the burner shown in Fig. 3; Fig. 5 is a sectional elevation of an insert member for use in a burner; Fig. 6 is a sectional elevation of a 25 modified form of insert member; Fig. 7 is a sectional elevation of a modified form of insert member; Fig. 8 is a sectional elevation of an insert member and a portion of a burner of modified construction.

30 Referring to the drawings, the burner shown in Fig. 1 is of the usual ring type in which there is the ring body portion 1 with a neck 2 and the mixing end 3, all of which are hollow, and the mixing end 3 has a central spider 4 with an opening through which the gas supply pipe with its proper orifice may be extended. The usual practice in burners of this type is to drill holes in the top surface of the ring portion of the burner, and at times it has been customary to provide the upper surface with short projections through which a hole is drilled. Under these conditions the gas passes directly from the chamber within the ring 45 member 1 through the openings in the top surface. These openings which extend through the top surface receive the full pressure of the gas, and it frequently happens that due to the pressure the gas blows itself out, or in other words, the flame is blown away from the top of the burner because of the pressure of the gas. It is difficult to control these matters except by the use of some special regulating mechanism which 50 is too expensive for installation in homes for

use in connection with water heating apparatus, heaters, and stoves, for domestic use.

In the present construction the top surface of the ring portion 1 is provided with a series of openings or depressions 5, which 60 openings or depressions at their inner ends have an outwardly extending ledge 6. Preferably these openings are circular and each of the openings is adapted to receive and retain an insert member 7. This insert 65 member may be of any desired form within the limits of the construction which is about to be described, but in the present instance it is made to be round. The member 7 is hollow, having an inner chamber 8, and the 70 top surface may be rounded as indicated in Fig. 5, or it may be otherwise constructed as shown in Figs. 6, 7 and 8.

The top surface has a plurality of holes through the same, as indicated at 9, which 75 holes communicate with the inner chamber 8. There is an opening through the wall of the member 7 which is opposite to the surface which is provided with port holes, this opening being indicated at 10, and is 80 of a diameter less than the diameter of the chamber 8 so that the rear wall of the member 7 forms what might be termed a ledge 11.

By reference to Fig. 6 it will be seen that the construction there shown of the member 85 7^a is in certain respects similar to that construction which has been previously described. The top surface, however, is flat and is provided with the opening 7^b. There is the inner chamber 7^c and the opening in 90 the rear wall of the chamber which is indicated at 7^d, this opening being of less diameter than the greatest diameter of the chamber.

In Fig. 7 there is shown a slightly different structure in which the member 7^e is provided with a rounding top indicated at 7^f, and a flat inside surface indicated at 7^g, so that the length of the ports which are formed in the top portion of the member are longer 100 at the center than they are toward the outer circumference.

There is an inner chamber 7^h and there is an opening 7ⁱ in the rear wall which is of less diameter than the greatest diameter of 105 the chamber 7^h.

This form of insert has been found very effective, in fact, in many respects it gives better results than the other forms of inserts in that it seems to provide a greater 110

friction to the gas passing through the openings in the center, thereby in a large measure preventing the "blowing out" of the gas at the central portion of the insert member.

In Fig. 8 a modified structure is shown in which the insert member 7¹ is provided with a chamber 7^k in which the rear wall is entirely removed, so that there is no opening or restricted diameter, as is the case with the other forms of inserts.

The burner structure in which the insert is inserted is indicated at 7^L and has a recess 7^m which at the lower part thereof is provided with an inwardly extending flange 7ⁿ which has an opening 7° which is of less diameter than the diameter of the opening 7^g.

The inner peripheral edge of the insert rests upon the inwardly extending flange 7ⁿ, and as will be noted, this flange 7ⁿ extends beyond the inner wall of the chamber 7^k.

It will be seen that in this structure by the use of the flange 7ⁿ in the burner structure proper, the same effect, so far as the chamber is concerned, is obtained with respect to the showing in Fig. 8 as is obtained with respect to the showing in Fig. 7.

The insert members as before stated are inserted in the openings which are formed in the ring portion 1, and the gas when supplied to the burner passes through the openings 9 in the inserts.

It is well a known fact that in burners of this character the gas in the burning receives what is known as primary air and secondary air, that is to say, at the mixer there is a certain amount of gas and air which are mixed, and this mixture passes through the burner and through the orifices of the burner, but when the gas and air mixture before described is burning there is a certain amount of air which is taken up from the atmosphere at the time of burning. The present burner is no different in this respect than those which have been heretofore used. However, due to the fact that the insert member 7 is hollow, and further, due to the fact that what may be termed the inlet opening in the rear wall of the insert is of less diameter than the chamber of the insert itself, the gas which enters the chamber of the insert is deflected and its pressure somewhat reduced so that the openings in the top surface of the insert, which openings are near the edge of the insert, are relieved from the high pressure, and therefore when the mixture of primary air and gas are ignited after passing through the insert members, the auxiliary air which is sucked in to complete the combustion, does not cause any blowing out due to the fact that the pressure of the gas which passes through the outside row of openings is diminished.

It should be noted that the insert members may be made of any desired material, good results having been obtained where the in-

sert was made of porcelain, and also where it was made of lava.

In Figs. 3 and 4 there is shown a slightly different form of burner, which is particularly intended for use in a vertical position. The burner consists of a head portion 13 with a neck portion 14 of increasing diameter, and at one end is the mixer portion 15. The head member 13 is provided with a plurality of depressions 16 in the same manner as has before been described, and in each of these depressions there is inserted an insert such as the insert 7 which functions in precisely the same way. In vertical burners of this kind the condensation which may drip from the coils of a water heater or any part of an apparatus in which such burners are used is liable to contact with the inserts and cause the flame to be extinguished. In order to protect these inserts the head portion 13 is provided with an extending flange 18 which extends slightly beyond the inserts so that the outer end of the flange is substantially in line with the lower portion of each insert so that condensation which may drip will impinge upon the flange 18 and be deflected so that it will not come in contact with the burner openings proper.

Having described my invention, I claim:

1. A gas burner comprising a hollow body having an opening, an insert member mounted in said opening, said insert member being hollow and having an outer wall which is rounded on its outer surface and flat on its inner surface, thereby providing a wall of varying thickness there being ports drilled through said wall.

2. A gas burner comprising a hollow body having an opening, an insert member mounted in said opening, said insert member being hollow and having an outer wall which has an outer rounded surface and a flat inner surface, thereby providing a wall of varying thickness, ports, drilled through said wall, said insert member having an inner wall with an opening therethrough which is of less diameter than the hollow interior of the insert member.

3. A gas burner comprising a hollow body having a recess in a wall thereof with an opening through the bottom wall of said recess which is of less diameter than the recess thereby providing a ledge, an insert member mounted in said recess, said insert member having a hollow interior communicating with the interior of the hollow body, the lower periphery of the insert member resting upon said ledge, said insert having an outer wall provided with a series of ports extending therethrough and a peripheral wall, both of said walls lying wholly within said recess.

4. A gas burner comprising a hollow body having a recess therein, with an opening through the bottom wall of said recess which

is of less diameter than the recess thereby providing a ledge, an insert member mounted in said opening, said insert member having a hollow interior communicating with the interior of the hollow body, the lower periphery of the insert member resting upon the said ledge, said insert having an outer wall with an outer rounding surface and an inner flat surface whereby there is provided a wall of varying thickness, and ports formed in said wall and extending therethrough.

5. A gas burner comprising a hollow body

having a head portion having an outer face, said face being provided with a plurality of openings, insert members in said openings, 15 which insert members are hollow and have a plurality of small holes extending through the outer wall thereof, said head being provided with an extending flange which overlies said insert members to deflect condensation.

In testimony whereof, I hereunto affix my signature.

JOHN P. REINECKE.
